UNITED STATES PATENT OFFICE.

WILLIAM C. TEMPLE, OF PITTSBURG, PENNSYLVANIA, ASSIGNOR TO THE AULTMAN AND TAYLOR MACHINERY COMPANY, OF MANSFIELD, OHIO, A CORPORATION OF OHIO.

STEAM-BOILER.

SPECIFICATION forming part of Letters Patent No. 742,931, dated November 3, 1903.

Application filed March 26, 1901. Renewed January 10, 1902. Serial No. 89,223. (No model.)

To all whom it may concern:

Be it known that I, WILLIAM C. TEMPLE, of Pittsburg, in the county of Allegheny and State of Pennsylvania, have invented a new and useful Improvement in Steam-Boilers, of which the following is a full, clear, and exact description, reference being had to the accompanying drawing, forming part of this specification, which shows in vertical section a steam-boiler constructed in accordance with my invention.

In the drawing, 2 represents the shell or brick setting of my improved boiler. 3 is the extension at the base thereof, which constitutes the grate-chamber, and 4 are grate-bars arranged therein.

5 5 is a steam-drum at the upper portion of the setting, and 6 is a mud-drum at the lower portion thereof, these drums being connected 10 by an annular bank of water-tubes 7, which preferably are inclined, so as to diverge somewhat downwardly and to constitute a downwardly-flaring interior space 8.

20 9 9 are baffles, which may be placed in the space 8 in order the better to direct the products of combustion among the tubes. The grate-chamber 3 does not open directly into the space among the tubes; but there is a baffle-wall 10, which surrounds the tubes at 30 the level of said chamber 3, an annular passage 11 being arranged between the baffle-wall and the shell 2 in order to permit the hot gases to pass from the chamber 3 and from the annular extension thereof 3', which extends around the baffle-wall.

35 The outlet-flue 12 of the boiler extends downwardly through the mud-drum 6 to the chimney.

40 As thus constructed the operation of the boiler is as follows: The flame and gaseous products of combustion from the chamber 3 pass around the wall 10, through the extension 3', and thence escape in an annular sheet through the passage 11 upwardly around and 45 among the tubes, the impetus which the gases receive in passing through the constricted passage 11 causing them to ascend rapidly toward the upper portion of the boiler-setting. The gases are then caused to descend

among the middle tubes of the bank and along 50 the same to the outlet-flue 12, so that they pass up and down in a recurrent course, as indicated by the arrows in the drawing. In this manner I secure very desirable results and obtain a boiler of high economy and efficiency.

55 It will be understood that the principles of my invention may be applied to boilers having their tubes and drums arranged somewhat differently from the construction shown 60 in the drawing, although I intend also to make specific claim to said construction, and that the arrangement of the combustion-chamber may be modified to adapt the boiler for burning gas instead of coal. Within the 65 scope of my broad claims the boiler may be adapted for use as a waste-heat boiler by reversing the flues, using the flue 12 through the mud-drum as an inlet for the hot gases and connecting the chamber 3' with an outlet-flue leading to the chimney.

I claim—

1. A boiler having upper and lower drums, an upwardly-extending bank of tubes, a baffle-wall outside the lower portion of the bank, 75 an inlet-flue and an outlet-flue for the products of combustion, one of said flues extending through the lower drum and communicating with the space among the bank of tubes, and the other flue communicating with the 80 space around the tubes by way of a passage outside said wall; substantially as described.

2. A boiler having upper and lower drums, an upwardly-extending bank of tubes, a combustion-chamber having a passage for the 85 gases extending upwardly among said tubes from the combustion-chamber above the level of the combustion-chamber and above that of the lower drum, and an outlet-flue for the gases extending through said lower drum and 90 communicating with the stack; substantially as described.

3. A boiler having an upwardly-extending bank of tubes, and a lower drum at the base of the tubes, a combustion-chamber, a baffle-wall shielding the tubes at the lower portion thereof, and an outlet for the gases extending through said lower drum, said combustion-

chamber being arranged to discharge its gases upwardly past the baffle-wall among the tubes; substantially as described.

4. A boiler having an upwardly-extending bank of tubes, a combustion-chamber, a baffle-wall shielding the tubes at the lower portion thereof, and an outlet for the gases extending through the lower drum at the base of the tubes, said combustion-chamber being arranged to discharge its gases upwardly, past the baffle-wall among the tubes, said tubes diverging downwardly; substantially as described.

5. A boiler having an upwardly-extending

bank of tubes, a combustion-chamber, a baffle-wall shielding the tubes at the lower portion thereof, and an outlet for the gases extending through the lower drum at the base of the tubes, said combustion-chamber being arranged to discharge its gases upwardly around and past the baffle-wall among the tubes; substantially as described.

In testimony whereof I have hereunto set my hand.

WILLIAM C. TEMPLE.
